UNITED STATES PATENT OFFICE.

PEARL F. FELL, OF HOLLIDAYS COVE, WEST VIRGINIA.

DESIGN FOR A CREAM-WHIPPER.

SPECIFICATION forming part of Design No. 34,098, dated February 19, 1901.

Application filed January 14, 1901. Serial No. 43,288. Term of patent 14 years.

To all whom it may concern:

Be it known that I, PEARL F. FELL, a citizen of the United States of America, residing at Hollidays Cove, in the county of Hancock and State of West Virginia, have invented and produced a certain new and useful Design for Cream-Whippers, of which the following is a specification, reference being had therein to the accompanying drawing.

The drawing disclosed is a perspective view of my new and original design for a cream-whipper, the leading or material feature of which design consists in the rim 1, with the concentric upwardly-extending handle 2, terminating at its upper end in a substantially heart-shaped ornament 3. The rim 1 has a wavy exterior appearance and the upwardly-extending handle a spiral effect. Concentric

of the lower end of the handle is a ring 4, which intermeshes with the arms 5, connected to the rim and to the lower end of the handle. The ring 4 lies within the substantially star-shaped series of arms 6, intersecting with the ring and with the rim at the point of intersection of the arms 5 with said rim.

Having thus fully described my invention, what I claim as new, and desire to secure by Letters Patent, is—

The design for a cream-whipper, substantially as herein shown and described.

In testimony whereof I affix my signature in the presence of two witnesses.

PEARL F. FELL.

Witnesses:

JOHN NOLAND,
E. E. POTTER.
